ABSTRACT

A lawn golf game playable with ordinary golf clubs and balls or wiffle balls on any reasonable size lawn area in leisure time by individuals or competitive teams which requires all the skill of conventional golf. Receptacles are located in a predetermined pattern or course above ground for receiving the golf ball. Each receptacle is cylindrically shaped and includes one closed end, one open end for receiving a ball, a lip extension for facilitating the entry of a ball into the receptacle, a conical projection adjacent the open end for anchoring the receptacle in place, and a post at the closed end for supporting an identifying flag and anchoring the receptacle in place.

GOLF GAME APPARATUS

BACKGROUND OF THE INVENTION

1. Field of the Invention

This invention relates to a lawn golf game, and, more particularly, to a golf game played with conventional golf clubs and balls or wiffle type balls on an ordinary lawn using receptacles fixedly located in a predetermined course in the ground but mounted above it.

2. Description of the Prior Art

Lawn and miniature golf games are well known. All of them require the traversal of a defined course and may use conventional golf clubs and balls or adaptations of such clubs and balls.

Some of these games are patterned after the game croquet using upright stakes, wickets and U-shaped bridge members as obstacles or goals which must be achieved. Other such games use receptacles but in all instances the receptacles are recessed in the ground.

None of the lawn golf games known in the prior art can be played using solely the instruments and rules of conventional golf and without requiring the permanent alteration or destruction of a lawn.

SUMMARY OF THE INVENTION

As contrasted with the prior art types of lawn golf games, the apparatus and game of the invention is played on an ordinary lawn using conventional golf clubs, balls and rules and without requiring the alteration or destruction of a garden lawn. Wiffle type balls may be employed in place of conventional golf balls. Specific receptacles are utilized having identifying flags removably mounted on them. The receptacles and flags are provided with suitable projections for insertion into the ground. In this way the receptacle and flag units are fixedly located at desired positions. The receptacles with differing identifying indicia are arranged in a desired pattern or course having a plurality of stations on and above an ordinary lawn by inserting the projections into the ground.

Using conventional golf clubs and balls or wiffle balls, the lawn golf game may be played by individuals or competing teams. Each player moves from receptacle to receptacle after causing his ball to enter the receptacle at the previous station. Individual and/or team scores are maintained as to the number of strokes required by each player or team to complete the course.

DESCRIPTION OF THE DRAWINGS

FIG. 1 is a diagram of a typical arrangement or course for playing the game of the invention; 50

FIG. 2 is a perspective view partially in section of a receptacle and identifying flag unit as mounted in the ground; and

FIGS. 3 and 4 are plan views of the rear and front faces of the receptacle, respectively.

DESCRIPTION OF THE PREFERRED EMBODIMENT

Referring now to FIG. 1, the lawn golf game according to the invention may be played on any garden lawn. A plurality of receptacles to be described more fully hereinafter are arranged in a typical pattern such as at the stations 1-9. Each station includes the receptacle unit receiving the ball and a tee for the next station proximately positioned near it.

As in conventional golf, the players begin at the first station or tee and proceed from station to station with the object of causing the ball to enter the receptacle at the next station. The lawn area required for the course is not required to be exceptionally large. It has been found that a lawn of approximately 5,000 square feet is adequate to play this game. The number of receptacles or stations can be optional dependent on the size of the available area. However, the lawn golf game according to the invention is patterned after the conventional game of golf with a minimum of nine receptacles. Two or three ordinary golf irons are all that are required for each

player. Regulation golf balls may be used. Alternatively, wiffle type balls may be employed in playing the game. In either case, the balls may be color coded to facilitate identification.

Referring now to FIG. 2, the receptacle according to the in-

vention is generally indicated at 10. It is cylindrical in shape and is provided with an opening 11 (FIG. 4) at one end that is at least as large as the diameter of the ball. Preferably this opening is approximately 1½ times the diameter of an ordinary golf ball. Receptacle 10 is mounted on the surface 12 of the ground. A projection 13 having a conical shape is provided for insertion into the ground and for locating the receptacle at a particular location or station on the course. To facilitate the entry of the ball into the receptacle an entrance lip or projection 14 is provided at the front end of the receptacle.

15 Receptacle 10 may be formed of a molded plastic material such that projection 13 and entrance lip 14 are formed as an integral part of the unit. Alternately, the receptacle may be metallic and have projection 13 affixed to it by suitable rivet elements or by welding or other means. Receptacle 10 has a length approximating 6 inches.

As shown in FIG. 3, receptacle 10 is provided with a screw projection 15 through its rear wall 16. Screw projection 15 is provided to accommodate an identifying indicium or flag 18 carried by a post 17. Post 17 is provided with a suitable conically shaped projection 19 for insertion into the ground. By employing the two projections 13 and 19 from the receptacle and from the post, assurance is provided that the position of the receptacle is not altered once fixed.

25 Post 17 is slotted at 20 to accept screw 15 extending through wall 16 of the receptacle and to provide vertical adjustment at a desired height for insertion into the ground. Locking of the post to the rear wall 16 of the receptacle is accomplished with a nut 21.

30 Flag 18 is shown as having a pennant shape. As is readily apparent the identifying indicium may take any of several forms being triangular or square-shaped mounted to post 17. The flag may also be formed of a rigid plastic or metallic material or it may be made from a cloth-like material to permit movement.

35 While the invention has been particularly shown and described with reference to a preferred embodiment thereof, it will be understood by those skilled in the art that the foregoing and other changes in form and details may be made therein 40 without departing from the spirit and scope of the invention.

45 What is claimed is:

1. Apparatus for use in playing a golf game on a playing surface with ordinary golf balls or wiffle type balls, comprising: a cylindrical shaped receptacle, said receptacle being closed at one end and open at the other end to receive a ball, and a substantially conically shaped projection fixed to a portion of the surface along the length of said receptacle and extending outwardly from said surface for insertion into the playing surface, said receptacle being fixedly located and in contact along said portion at a position above and on the playing surface when said projection is inserted into the playing surface; and

50 an entrance lip extending from the same portion of the surface of the receptacle as the projection and at the open end of said receptacle for facilitating the entry of a ball into the receptacle.

2. The apparatus of claim 1, and further comprising a post movably mounted to the closed end of said receptacle and an identifying indicium mounted to said post.

3. The apparatus of claim 2, and further comprising a substantially conically shaped projection extending from said post for insertion into the playing surface to fixedly locate the post.

4. A golf game playable with conventional golf clubs and balls or wiffle type balls on a lawn, comprising a playing surface;

55 a plurality of diversely located stations arranged in a progressive predetermined pattern on said surface, each of said stations having a receptacle for receiving a ball when directed at it;

each of said receptacles being characterized by being cylindrically shaped, said receptacles each being closed at one end and open at the other end to receive a ball,
 each of said receptacles including a substantially conically shaped projection fixed to a portion of its surface along its length and extending outwardly from said surface into said playing surface,
 said receptacles being fixedly located and in contact along said portion above and on said playing surface at the diverse locations of said predetermined pattern, and
 each of said receptacles including an entrance lip extending

from the same portion of the surface of the receptacle as the projection and at the open end of said receptacle for facilitating the entry of a ball into the receptacle.

5. The game of claim 4, wherein each of said receptacles further comprises a post movably mounted to the closed end of the receptacle in a direction perpendicular to the playing surface, an identifying indicium mounted to said post, and a substantially conically shaped projection extending from said post into the playing surface.
